Atty.

UNITED STATES PATENT OFFICE.

ANNA BRAND, OF CHICAGO, ILLINOIS, ASSIGNOR, BY MESNE ASSIGNMENTS, TO
HEALTH-TEX PRODUCTS CORPORATION, A CORPORATION OF ILLINOIS.

CATAMENIAL SACK OR NAPKIN HOLDER.

Application filed June 22, 1923. Serial No. 647,130.

To all whom it may concern:

Be it known that I, ANNA BRAND, a citizen of the United States, residing in Chicago, Cook County, Illinois, have invented 5 certain new and useful Improvements in Catamenial Sacks or Napkin Holders for Women, of which the following is a specification.

This invention relates to an improvement 10 in catamenial sacks or napkin holders for women.

The principal object of this invention is to provide a simple, reliable, light and unbreakable catamenial sack, so that it can 15 be applied by wearer at any time on short notice.

Another object of this invention is to provide a sack for napkin wearer, which while made out of elastic material is re-inforced 20 by a cord of non-elastic material which controls the elasticity and prevents the said sack from stretching to the breaking point.

Another object of this invention is to provide a catamenial sack or napkin holder 25 which can be conveniently folded and carried in any ordinary pocket or pocket book.

Another object of this invention is to provide a catamenial sack or napkin holder which can be easily attached to any ordinary belt. 30

These and other objects may be attained by means of the construction illustrated in the accompanying drawing, in which:

Figure 1 is a perspective view of the catamenial sack forming the subject of my invention. 35

Figure 2 is a plan view partly broken away and showing in dotted lines the sack stretched. 40

Figure 3 is a section on the line 3—3 of Figure 2.

Referring to the drawings, numeral 1 designates the body of the sack made out of pure rubber sheeting; numeral 2 shows 45 the non-elastic pieces of fabric or material attached to both ends of the sack by stitching or vulcanizing; numeral 3 shows the opposed side portions of sack turned inwardly to overlie the body portion of the sack and 50 provide a pocket for the absorbent pad; numeral 4 designates two loops or holders for retaining said absorbent pad, made also

of elastic material so as to stretch simultaneously with the stretching of the sack, to the extent of two inches on each side at 55 the same time, thus giving the sack a stretching capacity of four inches over its original size; numeral 5 designates a tubular seam stitched throughout the edges of the inwardly turned opposite side portions of 60 the sack, through which seam cord 6 is pulled, said cord being made of non-elastic fabric and run like a spring throughout the entire length of said sack and fastened into the non-elastic fabric at both ends thereof. 65

From the foregoing, it will be obvious that a catamenial sack made according to the above description, while affording all the comforts through its flexibility, will be 70 much more durable than any other sack, and practically unbreakable, in so far as loop 4, being made out of elastic material and stretching simultaneously with the sack, while allowing an expansion of two inches on each side at the same time, bringing the total length to 8 inches the cord 6, being made of non-elastic material, will control 75 and restrain such expansion, preventing it from stretching to a breaking point.

In other words, in my sack, the stretching capacity is limited to 2 inches on each side at the same time or to a total stretching capacity of 4 inches, by means whereof the wearer is prevented from tearing the sack and is afforded the greatest freedom of 80 movement without any danger of ripping or tearing it; in order to accomplish this end, in my sack the stretching capacity is limited to exactly two inches on each side. 85

I claim:

A catamenial sack comprising a strip of rubber sheeting having at each end a tab of non-elastic fabric, the opposed side portions of said strip being turned inwardly to provide a pocket for an absorbent pad, and having a tubular seam along the edges of said inwardly turned opposed side portions, and a serpentine or springlike cord of non-elastic material located in said seam and fastened at both ends thereof for the purpose of controlling the elasticity of said sack and restraining its stretching capacity from reaching a breaking point. 95 100

ANNA BRAND.
